[57] CLAIM

The ornamental design for an acoustical enclosure for
teleprinters or the like, substantially as shown.

DESCRIPTION

FIG. 1 is a front perspective of an acoustical enclosure,
showing our new design;

FIG. 2 is a top plan view thereof;

FIG. 3 is a right side elevation view thereof;

FIG. 4 is a front elevation view thereof;

FIG. 5 is a rear elevation view thereof; and

FIG. 6 is a bottom plan view thereof.

FIG. 1

FIG. 3

FIG. 2

FIG. 4

FIG. 5

FIG. 6
